UNITED STATES PATENT OFFICE.

WALFRID BURKMAN, OF CHICAGO, ILLINOIS, ASSIGNOR TO CHARLES H. FROST, OF SAME PLACE.

BRICK-MACHINE.

SPECIFICATION forming part of Letters Patent No. 364,395, dated June 7, 1887.

Application filed July 17, 1886. Serial No. 208,327. (No model.)

To all whom it may concern:

Be it known that I, WALFRID BURKMAN, residing at Chicago, in the county of Cook and State of Illinois, and a citizen of the United States, have invented a new and useful Improvement in Brick-Machines, of which the following is a full description, reference being had to the accompanying drawings, in which—

Figure 1 is a side elevation. Fig. 2 is a plan to view, the cover being removed. Fig. 3 is a horizontal section at line *x* of Fig. 1. Fig. 4 is a central vertical section at line *x* of Fig. 2. Fig. 5 is a vertical section at line *y* of Fig. 1. Fig. 6 is a detail, being a section at line *x* of Fig. 5. Fig. 7 is a detail, being a section at line *y* of Fig. 5. Figs. 8 and 9 are details, being side elevations of two blocks. Fig. 10 is a vertical section at line *z* of Fig. 1. Fig. 11 is a detail, being a plan of the hinged cover which carries the upper plungers.

This improvement relates to a hand-machine for making ornamental brick.

The objects of the invention are to provide improved devices for feeding the clay to the molds and giving pressure upon opposite sides of the brick, which I accomplish as illustrated in the drawings, and hereinafter described.

That which I claim as new will be pointed out in the claims.

30 In the drawings, A represents the main frame.

B is the hopper.

C is a fixed table secured at one side of the frame.

35 D is a fixed table on the opposite side of the frame.

E is a movable head or sweep for pushing the brick onto the table D.

v is a handle.

40 a a are two receptacles for clay located beneath the hopper. They are connected with the head or sweep E. The lower edges of the side pieces, b, of these receptacles slide upon

guides c upon the table C, and their upper edges slide in grooves in the wall of the hopper, as shown in Fig. 10. These side pieces,

45 b, extend to the rearward a considerable distance, and upon their top is a plate, F, which, when the clay-receptacles and head or sweep

E are moved forward, passes beneath the hopper and cuts off the flow of clay therefrom.

In the upper part of the main frame are two mold-boxes, G G, provided with suitable linings, as usual.

H H are two plungers, one for each of the mold-boxes G, which plungers are provided with facings at their upper ends. These plungers are bolted at their lower ends to a movable piece, I, which may be regarded as a part of the plungers, and which moves in a suitable guide, J. I is provided with a central screw-threaded opening which receives the screw K, which is keyed to a beveled pinion, L. The lower end of the shaft or screw K is supported in a suitable bearing in the frame.

M is a beveled pinion engaging with the wheel L. This pinion is upon a short shaft supported in suitable bearings, upon which shaft is a fly-wheel, N, on which there is a handle, d.

O is a cover hinged at e to the upper part of the frame.

f is a locking-catch operated by a lever, g, for the purpose of fastening the cover securely in place when it is closed.

P is a shaft supported in bearings in the cover O. This shaft is made eccentric at two points, h i.

Q Q are two plungers, each provided with a suitable facing, j, which plungers move in passages provided in the cover O.

k k are two blocks located in openings provided in the plungers Q, in which blocks the eccentric portions of the shaft P are located.

R is a hand-wheel on the shaft P.

The operation is as follows: When the machine is to be ready for use, the cover must be first thrown back upon its hinges, carrying with it the plungers Q, and leaving the mold-boxes exposed. Then the clay-receptacles a, being full, are to be pushed forward by an operator, who takes hold of the handle v, until the clay-receptacles come over the mold-boxes, into which the clay will fall from the receptacles a, and at the same time the plate F will come beneath the lower end of the hopper and cutoff the flow of clay. The receptacles a, with

the head or sweep E and plate F, are then to be returned to the position shown in Fig. 4. Then the cover O is to be closed and secured in place by means of the lock-latch. Then an operator by rotating the wheel N will give an upward motion to the plungers H through the action of the pinion M, wheel L, and screw K, giving the required pressure upon the under side of the brick. Then by rotating the hand-wheel R the operator can give pressure upon the uppersurface of the brick in the two molds, the rotation of the shaft P and the action of the eccentric *sh*i forcing the plungers Q Q down a little. The movement of these plungers downward is slight, the main pressure having been given from below. Then the operator is to release the latch and throw the cover O back. Then by continuing to rotate the wheel N the plungers H H can be forced upward, carrying the lower edges of the two pressed bricks in the molds up to a line with the delivery-table D. Then the operator again pushes forward the head or sweep E, which, coming in contact with the brick, will force them onto the delivery-table D. Then the plungers H are to be returned to their former position and clay will again be delivered from the receptacles *a* to the mold-boxes. Then the clay-receptacles and sweep are to be returned to the position shown in Fig. 4. The cover is to be again turned down, and the described operation of pressing the brick and delivering the same to the table D is to be repeated.

It will be observed that I give the main pressure by means of the lower plungers, the upper plungers while this first pressure is being given remaining stationary, and that I then give a final pressure upon the upper surfaces of the brick, the lower plungers remaining stationary while such final pressure is being given. I find in practice that there are advantages from this method, among which are, that the top of

the completed brick is near the top of the mold-boxes, so that it requires less movement of the lower plungers to lift the brick out from the mold-boxes. I also find that by this method I can make a finer and better ornamental brick than heretofore. The lower plunger or die may be provided with any suitable ornamental figure.

50

What I claim as new, and desire to secure by Letters Patent is—

1. In a brick-machine, a main frame provided with one or more mold-boxes, in combination with a cover, O, carrying one or more plungers, Q, and a shaft, P, supported in the cover and provided with an eccentric for each of said plungers Q, substantially as and for the purpose specified.
2. In a brick-machine, a main frame provided with one or more mold-boxes, a cover, O, carrying one or more plungers, Q, and a shaft, P, provided with an eccentric for each of said plungers, in combination with a head or sweep, E, and one or more clay-receptacles, *a*, substantially as and for the purpose specified.
3. In a brick-machine, a main frame provided with one or more mold-boxes, a cover, O, carrying one or more plungers, Q, and a shaft, P, provided with an eccentric for each plunger Q, in combination with one or more plungers, H H, substantially as and for the purposes specified.
4. In a brick-machine, a main frame and one or more mold boxes, in combination with a cover, O, carrying one or more plungers, Q, and a shaft, P, provided with an eccentric for each plunger, one or more plungers, H, and screw K, substantially as and for the purposes specified.
